UNITED STATES PATENT OFFICE.

CHARLES WILLIAM BARTON, OF PORTSMOUTH, OHIO.

AUTOMATIC INJECTOR.

Application filed July 7, 1928. Serial No. 121,033.

This invention relates to a safety device in the form of an injector adapted for use in connection with steam boilers, the primary object of the invention being to provide means for automatically replenishing the supply of water in a boiler when the water has reached a dangerously low level therein.

Another object of the invention is to provide means for automatically sounding an alarm when the water in the supply tank has been exhausted, thereby indicating to the operator of a dangerous condition of the water supply.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an enlarged sectional view through an ejector constructed in accordance with the invention.

Figure 2 is a diagrammatic view illustrating the application of the ejector.

Referring to the drawings in detail, one end of a boiler is indicated by the reference character 5, which is supplied with the usual water gauge 6 for determining the water level in the boiler 5 at all times.

Communicating with the usual transparent tube of the water gauge 6 through the medium of the elbow 7, is a pipe 8, that has its forward end connected with pipe 9, through the elbow 10, the latter pipe being in communication with the valve chamber 11, as clearly shown by Figure 1.

An exhaust pipe indicated at 10' extends into the valve chamber 11 so that when the valve to be hereinafter more fully described, has been moved to its normal position, steam may exhaust therefrom.

Communicating with the lower end of the water gauge 6 is a pipe 12 which is substantially long and extends forwardly where it has communication with the pipe 13 through the T-joint 14, the pipe 13 being in communication with the pipe 8 through the T-coupling 15.

The T-joint 14 embodies an extension 16 that connects with the lower end of the arm

17 which is pivotally connected through the bracket 18, at 19, the upper end of the arm having pivotal connection with the valve rod 20 that carries the valve 21 on its forward end.

Communicating with the valve chamber 11 is a pipe 22 that has communication with the pipe 23 through the pipe 24, the pipe 23 being in communication with the pipe 25 that has an upwardly extended end portion 26 extending into the valve chamber 27 in which the valve 28 operates.

As illustrated by Figure 1, the valve member 28 is normally open to permit steam to pass through the valve chamber 27 for purposes to be hereinafter more fully described.

The valve chamber 27 forms a part of the injector which embodies a pipe having an enlarged portion 29 that houses the float 30 secured at one end of the bell crank lever 31 that has connection with the rod 32 which connects with the valve 28 so that movement of the float 30 will operate to move the valve 28 within the valve chamber 27 to accomplish various results.

The reference character 33 indicates a whistle which is designed to receive steam passing through the valve chamber 27 when the valve member 28 has moved inwardly to allow steam to pass into the whistle.

It will be obvious that such a movement of the valve 28 will occur when the water in the feed pipe and enlarged portion 29 thereof falls below a predetermined level in the pipe or below the float 30, whereupon the float will drop downwardly moving the valve 28 to admit steam to the whistle.

The pipe 34 communicates with the enlarged portion 29 of the feed pipe, which pipe 34 is divided by the wall 35 that is formed with an opening providing a seat for the valve 36 carried on the inner end of the valve rod 37 there being provided a piston 38 on the opposite end of the rod 37 to receive the action of the coiled spring 39 to move the rod 37 in one direction, and to receive the force of steam passing through pipe 40, to move the rod 37 in the opposite direction.

This piston 38 moves in the cylinder 41, which is supported by the rods 42 that extend through openings in the flange 43 of the cylinder, the rods also passing through openings in the removable head 44, as shown by Figure 1.

The main or body portion of the injector

is indicated at 45 and is in communication with the upper end of the pipe 34 at 46, so that when the valve member 36 is moved to its open position, fluid may pass upwardly into the injector body 45, to accomplish the purpose of the invention.

The body portion of the injector is divided through its central portion by means of the wall 47 thereby providing a front compartment 48 and a rear compartment 49, the wall 47 having a threaded opening to receive the threaded portion of the nozzle 50 which has a discharge flared end 51 extending an appreciable distance within the compartments 48.

15 The inner end of the nozzle 50 is tapered defining a seat for the valve 52 carried at the inner end of the rod 53 which in turn has a piston 54 mounted on its outer end. This piston 54 operates in the cylinder 55 and is 20 held to the limit of its inward movement by means of the coiled spring 56, there being provided an opening 57 at the opposite end of the cylinder 55 in which one end of the pipe 58 is positioned, which in turn connects with 25 the pipe 59 through the elbow 60, the latter pipe being in communication with the cylinder 41, at a point beyond the piston 38.

The pipe 61 is in communication with the compartment 49 that in turn is in communication with the upper portion of the boiler 30 for the purpose of supplying steam to the compartment 49 and nozzle 50 when the valve 52 has been moved to its open position.

Connected with the body portion of the injector is a water feed pipe 62 that is also in communication with the boiler to supply water thereto, when the supply of water has reached a dangerously low level in the boiler.

From the foregoing it will be obvious that 40 should the water level in the boiler 5 reach a dangerously low point, the pipe 12 will expand or move forwardly, moving the arm 17 and valve rod connected therewith to cause the valve member 21 to move rearwardly, 45 opening the passageway through the valve chamber 11 allowing steam in the boiler to pass through pipe 23, pipe 25 and pipe 26 from where it passes through the valve chamber 27, pipe 40 and into the cylinder 41 behind the piston 38, whereupon the steam pressure will force the rod 37 rearwardly, unseat-

ing the valve 36 and allowing water to pass upwardly into the compartment 48.

As the piston 38 moves within the cylinder 41, the opening to the pipe 59 will be cleared 55 and steam will be permitted to pass into the cylinder 55 through pipe 58, the steam acting against the piston 54 to unseat the valve 52, and allowing steam from the boiler to pass through pipe 61, compartment 49 and 60 into the nozzle 50, where the steam is discharged through the flared extremity 51 of the nozzle, which steam acts as an injector to force water through the pipe 63 and into the feed pipe 62 from where it passes to the 65 boiler to replenish the water supply therein.

Should the water in the supply pipe and supply tank become exhausted, it is obvious that the float 30 will fall downwardly moving the valve 28 to a position to allow steam 70 to pass into the whistle 33 and sound an alarm to indicate to the attendant the condition of the water supply.

It will be obvious that as the cold water enters the boiler, the pipe 12 will contract to move the valve 21 to its normal position shutting off the steam supply and allowing the spring 39 and spring 56 to reseat the valves and cause the various elements of the injector to assume their normal positions.

I claim:

In combination with a steam boiler, an automatic injector including a body portion formed with a dividing wall dividing the body portion into front and rear compartments, a nozzle supported in the dividing wall, a valve within the rear compartment for normally closing the nozzle, a pipe establishing communication between the front compartment and boiler, a pipe for establishing communication between the rear compartment and boiler to deliver steam to the rear compartment, a water feed pipe connected with the body portion, a valve for normally preventing water from entering the body portion, and thermostatically controlled means for operating the valves to simultaneously admit steam and water to the body portion to inject water into the boiler.

In testimony that I claim the foregoing as my own, I have hereto affixed my signature.

CHARLES WILLIAM BARTON.
